UNITED STATES PATENT OFFICE.

JOHN H. SWARTZ, OF BROOKLYN, ASSIGNOR TO DE WITT C. TAYLOR,
OF NEW YORK, N. Y.

WATER-METER.

SPECIFICATION forming part of Letters Patent No. 243,087, dated June 21, 1881.

Application filed September 29, 1880. (No model.)

To all whom it may concern:

Be it known that I, JOHN H. SWARTZ, of Brooklyn, in the county of Kings and State of New York, have invented an Improved Water-Meter, of which the following is a specification.

Figure 1 is a horizontal section of my improved water-meter, taken on the plane of the line *c c*, Fig. 2. Fig. 2 is a side view, partly in section, of the same, the line *c k*, Fig. 1, indicating the plane of section. Fig. 3 is a vertical cross-section thereof on the line *k k*, Fig. 1. Fig. 4 is a horizontal section on the line *q q*, Fig. 2. Fig. 5 is a vertical section on the line *k q*, Fig. 4.

This invention relates to water-meters of that class which measure a stream of water by the effect which a certain portion of the stream that passes through the meter-box has upon the registering mechanism.

Heretofore meters of this class were regulated, principally, by a valve at the inlet-opening—that is to say, at the opening at which the water flows into the meter; but I found by many experiments that satisfactory results are not obtainable wherever there is a valve at the inlet-opening, because greater or less obstruction is necessarily placed into the path of the water as it flows into the meter, and therefore friction created, which will interfere with the proper measuring of whatever portion of the stream is allowed to enter the meter.

My invention consists, principally, in constructing a meter into which the water flows without any attempt at obstruction or regulation whatsoever, but the outlet of which is supplied with a valve for producing the requisite degree of adjustment and regulation; this in contradistinction to the usual obstruction or valve at the inlet.

The invention also consists in other details of improvement, which are hereinafter more fully described.

In the drawings, the letter *A* represents the inlet-pipe, the letter *B* the meter-chamber, and the letter *C* the outlet-pipe, of the meter. The inlet-pipe connects in suitable manner with the supply-pipe, and contains a partition, *a*, which forms a narrow channel, *b*, through which part of the stream passes from the inlet-pipe into

so that the water that enters said meter-chamber *B* will revolve the vanes *D* of the recording mechanism. The main body of the stream, however, from the inlet-pipe *A*, lifts a valve, *E*, (see Fig. 2,) and passes through a side channel, *F*, directly into the outlet-pipe *C*. 55

The valve *E* has a downwardly-extending stem, *e*, which is, below the pipe *A*, connected with a suitable spring or series of springs, *G*, as clearly shown in Fig. 2. The tension of this spring or set of springs *G* is regulated to maintain the desired proportion of stream passing by the meter by means of a sliding block, *f*, which is moved by a suitable screw, *g*, or in any other suitable manner, so that by sliding 65 said block *f* and adjusting the power of the spring or springs, the meter will be adjusted to require more or less water-power to lift the valve *E*. Suitable ears, *h*, projecting from the valve straddle pins *i*, as shown in Fig. 2, and 70 prevent the valve *E* from turning, and from being lifted too high. Thus it will be seen that the passage from the pipe *A* to the meter-chamber *B* is always unobstructed and always the same in size, permitting so much of the 75 stream to enter the meter-body unobstructedly as is not permitted to pass through the chamber *F*. A suitable proportion is thus allowed to enter a branch pipe, *F*, without affecting the meter. By means of the adjusting mechanism 80 described the valve *E* can be more or less loaded either from above or below, to regulate the degree of force necessary to lift it, and consequently the proportion of the stream admitted into the branch pipe *F*. The water having 85 passed through the channel *b* into the lower part of the meter-chamber *B*, where the vanes *D* are located, (see Fig. 5,) passes next through a hole, *j*, in a partition, *l*, which is placed above the lower part of the meter-chamber into the 90 upper part, *m*, of said meter-chamber, and thence through a lateral hole, *n*, into the pipe *C*, as clearly shown in Fig. 5.

The size of the opening *n*, through which the water is discharged from the meter-body, is 95 regulated by suitable sliding piece, *p*, and screw *r*, or other equivalent mechanism, so that the discharge of the water from the meter is more or less obstructed, according to the amount of water and degree of pressure or head that is 100

conducted toward the meter. Thus, if a small stream of water with a reduced head enters the inlet-pipe A, the valve or slide p may be lowered to reduce the outlet-opening, where-
5 as for a greater head of water and larger main stream said valve may be raised to increase the outlet-opening.

Normally, the outlet-opening n should be larger in cross-section or area than the channel 10 b . By my arrangement of adjusting the inlet to the side channel and the outlet of the measuring part of the stream the requisite proportion between the two streams can at all times be insured.

15 I claim—

1. In a water-meter, the combination of interior partition, l , having center vent, j , with the shell or case B, having unobstructed inlet-channel b , to allow free ingress of water into 20 the measuring part of the meter, and with the regulating-valve p at the outlet-opening n , substantially as described.

2. The shell B of a water-meter, provided with the unobstructed inlet-passage b and 25 larger outlet-opening n , in combination with

the valve E and side branch, F, and with the valve p , substantially as described.

3. A water-meter having inlet-channel b , and side passage, F, and outlet C, in combination with the valve E and valve p , both said valves 30 regulating the amount of water going into the outlet-pipe, substantially as described.

4. The valve E, pipe A, branch pipe F, unobstructed branch pipe b , and partition l , in combination with the spring G, and with mechanism 35 for regulating the weight or pressure of the valve, substantially as described.

5. In a water-meter, the combination of the inlet-pipe A, having channel b and partition a , with the meter-chamber B, having outlet-opening n , and the partition l , having passage j 40 and the valve p , branch pipe F, and outlet-pipe C, for operation substantially as described.

This specification signed by me this 27th day of September, 1880.

JOHN H. SWARTZ.
